UNITED STATES PATENT OFFICE.

SAMUEL S. STOLP, OF CHICAGO, ILLINOIS, ASSIGNOR TO CHARLES B. GILLSON, OF CHICAGO, ILLINOIS.

DIRECT-CURRENT TRACK-CIRCUIT FOR RAILWAY SIGNALS.

Application filed February 24, 1920. Serial No. 280,613.

The invention relates to railway signals and particularly to the so-called track circuit comprising a source of direct current, the rails of the track in a given section or block and the track relay by which the operation of the corresponding signal mechanism is controlled. The invention is more especially applicable to those track circuits in which primary cells or a storage battery, having low internal resistance, is employed as the source of current.

While external resistance is commonly employed to limit the outflow of current from the battery, the amount of this limiting resistance is usually constant and it is in circuit at all times. It follows that the greatest limiting resistance which can be used is therefore only that which will permit the greatest current flow required at any time. Many track circuits now in use accordingly present the anomalous condition that the consumption of battery current during all of the time that the track is unoccupied is equal to that which is only momentarily required at the instant the train shunt is removed and many times this amount of current is used when the track is occupied and no work is being done. The track battery accordingly requires renewal much more frequently than should be necessary and the delay of a train within the block may so exhaust the battery that the signal will fail to operate when traffic is again restored.

Obviously an ideal condition would be one in which an abundance of current is momentarily supplied for the pick up of the track relay when the train moves out of the block with only the minimum amount of current necessary to prevent release of the relay furnished during the remainder of the time that the track is unoccupied and no current at all supplied when the train is in the block. On the other hand, there will be no premature exhaustion of the battery by delayed trains if the amount of current supplied when the track is occupied is not greatly in excess of that supplied when the track is unoccupied and it is believed to be impracticable to completely open circuit the battery at any time.

The object of the present invention is to provide an improved track circuit in which the foregoing desirable condition is substan-

tially obtained and the consumption of battery current is greatly reduced. To this end, the invention contemplates in the first instance, the momentary cutting out of all battery limiting resistance at the instant the train shunt is removed with preferably the use of a relatively high limiting resistance during the remainder of the time when the track is unoccupied in all cases where the condition of the ballast will permit, and the introduction of a still larger limiting resistance when the train shunt has been applied. Increased safety and a greater certainty of signal operation are thereby both obtained in addition to economy of battery current. A feature of the invention also provides for the momentary use of a supplemental battery in series with the track battery whenever increased voltage is desirable for accomplishing pick up of the track relay.

The accompanying drawing is a conventional representation of one form of the improved track circuit.

The insulated rails of a single section of track are indicated at 10 and 11. The track relay is represented at 12, the relay leads being shown at 13 and 14. The train shunt is represented at 15 and the ballast shunt at 16. These parts are all as usual in direct current track circuits except that when desired the length of the circuit may be greater than has heretofore been customary.

The track battery comprising three primary cells of low internal resistance connected in multiple is indicated at 17. When a supplemental battery is used it may be located as shown at 18. This supplemental battery may consist of a single cell of like low internal resistance with each cell of battery 17. The supplementary battery 18 is employed only momentarily for the pick up of track relay 12 and is then connected in series with battery 17. In the arrangement illustrated it is on open circuit at all other times.

One side of track battery 17 is permanently connected to rail 11 through battery lead 19. The other side of the track battery 17 is connected to rail 10 through limiting resistance 20, control relay 21 and lead 22. Also, when the track is unoccupied, there is a shunt path for current around relay 21 comprising lead 23, connected to the remote

end of limiting resistance 20 from the battery 17, supplemental limiting resistance 24, back contact 25 of relay 21 and lead 26, the latter extending from the armature 27 of 5 relay 21 to lead 22. The normal battery limiting resistance when the track is unoccupied is thus limiting resistance 20 plus the effective resistance of relay 21 and supplemental limiting resistance 24 in parallel, plus 10 the resistance of leads 19 and 22. Furthermore, the proportion of current passing through the control relay 21 is determined by the adjustment of resistance 24 with respect to the resistance of relay 21. In the 15 arrangement shown in the drawing the current passes through relay 21 when the track is unoccupied, but not in sufficient strength to cause this relay to pick up, first because relay 21 is joined in parallel with resistance 20 20 and second, because the total current strength is reduced by the resistance of the track relay 12.

When the train shunt 15 is applied, control relay 21 picks up, and back control 25 being opened, all of the current passes through relay 21. The picking up of relay 21 when the train shunt 15 enters the block is due to the fact that the short circuiting of the resistance of track relay 12 increases 30 the total current strength to such an amount that the part passing through relay 21 is greater than the pick up constant of this relay. The battery limiting resistance is thus increased and becomes limiting resistance 20 plus the resistance of relay 21 and leads 19 and 22. It should be observed that just as soon as relay armature 27 has been lifted clear of its back contact 25, all of the current must pass through relay 21 and complete pick up of this relay is insured. Should track relay 12 have failed to drop from the application of the train shunt 15 alone, it will certainly be released by the pick up of control relay 21, due to the increased battery limiting resistance thereby inserted.

A second relay 28, shown as having two front contacts 33 and 34, is also used at the battery end of the circuit. This relay is 50 preferably constructed for retarded release, as by being formed with a copper sleeve 29 on the core. As shown, the relay 28 is on open circuit when the track is unoccupied. Upon the application of the train shunt, as 55 15, relay 28 is bridged across the track, as by being connected by lead 30 to battery lead 19 at one side, and by lead 31, front contact 32 of relay 21 and lead 26 to lead 22 at the other side. The addition of this shunt across 60 the track promotes safety and it also draws more current through relay 21 for holding the same, thus providing a safeguard against any accidental release of relay 21 while the train shunt, as 15, is applied. It is the intention that relay 28 shall receive a pick up 65

current only upon removal of the train shunt, as 15.

When relay 28 picks up, the closing of its front contact 33 provides a direct path for current across the terminals of relay 21 70 whereby relay 21 releases. This in turn puts relay 28 again on open circuit, due to the opening of front contact 32 of relay 21, but delayed release of relay 28 does not permit the opening of either of its front contacts 33 75 or 34 until pick up of the track relay 12 has been accomplished. As shown, the closing of front contact 33 of relay 28 bridges the terminals of relay 21 through a wire 35, which connects one of the arms, as 36, of the 80 armature of relay 28 with lead 23, and a wire 27 which connects front contact 33 with lead 22.

The other arm, as 38, of the armature of relay 28 is also connected to lead 23 by a 85 wire 39. It therefore follows that while front contact 34 of relay 28 is closed, there is a direct path for current from supplemental battery 18 to lead 22 through lead 40, front contact 34, armature arm 38, wires 39, 35, armature arm 36, front contact 33 and wire 37. Battery current of increased voltage with no limiting resistance is thus momentarily supplied to the track for accomplishing pick up of the track relay 12. If 90 supplemental battery 18 were omitted, then the full current strength of track battery 17 alone would be momentarily applied to the track without limiting resistance. In many cases this would be sufficient. 100

It will be observed that when front contacts 33 and 34 of relay 28 are closed, lead 23 and battery limiting resistance 20 afford an alternate path for current around the supplemental battery 18. Owing to the low 105 internal resistance of battery 18, this alternate path for current has but little effect in reducing the voltage obtained by connecting batteries 17 and 18 in series. Opening of front contact 33 in advance of the opening of front contact 34 is to be avoided by a suitable adjustment of these contacts in a well known manner, for with front contact 33 open and front contact 34 closed, a current impulse having the combined voltage 110 of batteries 17 and 18 would be applied to relay 21. 115

If relay 28 should fail to pick up on removal of the train shunt, relay 21 would never release for, when its back contact 25 has been opened, there is no alternate path for current to the track and all of the current passes through the said relay 21. Accidental release of relay 21 before pick up of relay 28 has been accomplished is therefore prevented. 120

Except when the ballast shunt 16 is so favorable that the track relay 12 can receive a pick up current from battery 17 125 alone with a battery limiting resistance 130

equal to limiting resistance 20 plus the resistance of relay 21, the operativeness of the circuit to clear the signal upon removal of the train shunt depends upon a pick up current being supplied to relay 28 over the ballast and track relay shunts 16, 12. However, since accidental pick up of relay 28 while the train shunt is applied (resulting from foreign current, for example) would not cause a false clear signal to be shown, relay 28 may, without danger, be made of low resistance as compared with the resistance of the track relay 12 and ballast shunt 16 and such a construction of the relay is preferred.

When relay 28 is of the said low resistance, it receives the major part of the current as soon as the train shunt is removed and the circuit is operative until ballast becomes so unfavorable that pick up of the track relay 12 would be useless because of insufficient current for holding. On the other hand, if desired, relay 28 may be constructed with opposed windings of like resistance, one of which (not shown) is connected across the battery 17 when relay 21 picks up while the other winding is connected across the track in the manner represented for the single winding shown in the drawing. When the train shunt, as 15, is applied the two windings receive nearly equal amounts of currents and counter balance each other. When the train shunt is removed, the effective resistance of the ballast shunt 16 and track relay 12 is added to one of the windings with the result that the major part of the current passes through the other winding and pick up of relay 28 is accomplished even with very unfavorable ballast. Additional current may also be supplied to the relay 28, when desired, by connecting this relay to the battery leads adjacent the battery with respect to the limiting resistance 20 and relay 21 instead of at the remote side of the said limiting resistance and relay from the battery, as shown.

The following tables of assumptions and calculations of results by Ohm's law are given for the purpose of illustrating the operativeness of a circuit arranged in accordance with the drawing.

Table of assumptions.

55 Circuit length=2500 feet.
Combined resistance of rails 10, 11=0.25 ohm.
Resistance of battery leads 19, 22,=0.06 ohm.
60 Resistance of relay leads 13, 14,=0.10 ohm.
Ballast (average)=3.2 ohms.
Resistance of track relay 12=4 ohms.
Pick up constant of track relay 12=.078 amp.

Release constant of track relay 12=.037 amp.

Battery 17=0.65 volts.

Battery 18=0.65 volts.

Limiting resistance 20=1 ohm 70

Limiting resistance 24=1 ohm}=1.5 ohm.

Resistance of relay 21=1 ohm

Pick up constant of relay 21=.150 amp.

Resistance of relay 28=1 ohm.

Pick up constant of relay 28=.125 amp. 75

Resistance of poorest train shunt=.06 ohm.

Table of calculated results.

Current @ relay 21 when track is unoccupied=.093 amp.

Initial pick up current @ relay 21 when train shunt 15 is applied at relay end of track=.175 amp.

Follow up current @ relay 21 when train shunt 15 is applied and back contact 25 of relay 21 has been opened=.275 amp.

Holding current @ relay 21 when train shunt has been applied and front contact 32 of relay 21 is closed=.288 amp. 80

Current @ relay 28 when train shunt 15 is applied at relay end of track=.076 amp.

Pick up current supplied to relay 28 when train shunt is removed (average ballast)=.175 amp. 85

Minimum resistance of ballast shunt 16 over which pick up current equal to pick up constant of relay 28 upon removal of train shunt=.65 ohm.

Holding current supplied to track relay 12 when track is unoccupied (average ballast)=.080 amp.

Pick up current momentarily supplied to track relay 12 upon removal of train shunt (average ballast)=.280 amp.

Total current consumption track unoccupied=.186 amp.

Total current consumption track occupied=.316 amp.

Current furnished by the supplemental battery 18 does not appear in the figures given for total current consumption for the reason that this battery is only momentarily in circuit and its deterioration is negligible.

110 I claim as my invention:

1. The method of operating a closed track circuit having a battery limiting resistance which consists in increasing the battery limiting resistance when the train shunt is applied and momentarily closing a shunt around the battery limiting resistance upon removal of the train shunt. 115

2. The method of accomplishing pick up of the track relay in a closed track circuit having a track battery which consists in momentarily connecting another battery in series with the track battery.

3. The method of accomplishing pick up of the track relay in a closed track circuit 130

having a track battery which consists in momentarily connecting another battery in series with the track battery without opening the track circuit.

5 4. The method of accomplishing pick up of the track relay in a closed track circuit having a track battery and battery limiting resistance which consists in momentarily closing a shunt around the battery limiting resistance and at the same time connecting another battery in series with the track battery.

10 5. The method of operating a closed track circuit having a track battery and battery limiting resistance which consists in increasing the battery limiting resistance when the train shunt is applied and momentarily closing a shunt around the battery limiting resistance upon removal of the train shunt and 20 at the same time connecting another battery in series with the track battery.

15 6. The method of operating a closed track circuit having a track battery and a normal battery limiting resistance which consists in introducing an additional battery limiting resistance when the train shunt is applied and 25 momentarily closing a shunt around both the said normal and additional battery limiting resistance upon removal of the train shunt.

30 7. The method of operating a closed track circuit having a track battery and a normal battery limiting resistance which consists in introducing an additional battery limiting resistance when the train shunt is applied and 35 momentarily closing a shunt around both the said normal and additional battery limiting resistances upon removal of the train shunt, and at the same time connecting another battery in series with the 40 track battery.

45 8. The method of operating a closed track circuit having a track battery and a normal battery limiting resistance which consists in introducing an additional battery limiting resistance when the train shunt is applied and 50 momentarily closing a shunt around both the said normal and additional battery limiting resistances upon removal of the train shunt, and at the same time connecting another battery in series with the track battery without opening the track circuit.

55 9. The method of operating a track relay through the rails of a track which consists in supplying a holding current to the track rails from a battery unit after pick up of the relay has been accomplished and momentarily supplying current to the track rails from an additional battery unit connected in series for accomplishing the pick up.

60 10. The method of operating a track relay through the rails of a track which consists in supplying a holding current to the track rails from a current source of predetermined voltage after pick up of the relay has been

accomplished and momentarily supplying current to the track rails from a current source of higher voltage for the pick up.

11. The method of operating a closed track circuit having a track battery and a 70 battery limiting resistance which consists in momentarily closing a shunt including an additional battery around the battery limiting resistance upon removal of the train shunt.

75 12. The method of operating a closed track circuit having a track battery and battery limiting resistance which consists in increasing the battery limiting resistance when the train shunt is applied and momentarily closing a shunt including an additional battery around the battery limiting resistance upon removal of the train shunt.

80 13. The method of avoiding excessive consumption of battery current during the application of the train shunt to a closed track circuit having battery limiting resistance divided into two parts arranged in parallel branches of the circuit which consists in opening one of the said parallel branches of 85 the circuit when the said train shunt is applied.

90 14. The combination with a closed track circuit comprising the rails of the track, a track battery, a track relay and a battery limiting resistance, of a normally open shunt around the battery limiting resistance, a supplemental battery in said shunt and means for closing the said shunt.

95 15. The combination with a closed track circuit comprising the rails of the track, a track battery, a track relay and a control relay between the battery and track, of a back contact for the said control relay and a shunt of predetermined resistance around the control relay opening at its said back contact.

100 16. The combination with a closed track circuit comprising the rails of the track, a track relay, a track battery and a battery 110 limiting resistance and control relay between the battery and track, of a back contact for the said control relay and a shunt of predetermined resistance around the control relay opening at its said back contact.

115 17. The combination with a closed track circuit comprising the rails of the track, a track relay, a track battery and a control relay between the battery and track, of back and front contacts for the said control relay, 120 a shunt of predetermined resistance around the control relay opening at its said back contact and a shunt of predetermined resistance across the rails of the track opening at the front contact of the control relay.

125 18. The combination with a closed track circuit comprising the rails of the track, a track relay, a track battery and a control relay between the battery and track, of a back contact for the control relay, a shunt of 130

predetermined resistance around the control relay opening at its said back contact, a normally open low resistance shunt around the said control relay, and means for closing the said low resistance shunt.

19. The combination with a closed track circuit comprising the rails of the track, a track relay, a track battery and two battery limiting resistances arranged in parallel branches of the circuit, of means for opening one of the said circuit branches, a normally open low resistance shunt around both of the said branches of the circuit, and means for closing the said low resistance shunt.

20. The combination with a closed track circuit comprising the rails of the track, a track relay, a track battery and two battery limiting resistances arranged in parallel branches of the circuit, of means for opening one of the said circuit branches, a normally open low resistance shunt around both of the said branches of the circuit, a supplemental battery in said low resistance shunt, and means for closing the said low resistance shunt.

21. The combination with a closed track circuit comprising the rails of the track, a track relay, a track battery and a control relay between the battery and track, of a front contact for the said control relay, a shunt across the track opening at the front contact of the control relay, a second relay in said shunt, a front contact for the last mentioned relay and a low resistance shunt around the control relay opening at the said front contact of the other relay.

22. The combination with a closed track circuit comprising the rails of the track, a track relay, a track battery and a control relay between the battery and track, of a front contact for the said control relay, a shunt across the track opening at the front contact of the control relay, a retarded release relay in said shunt, a front contact for the retarded release relay and a low resistance shunt around the control relay opening at the said front contact of the retarded release relay.

23. The combination with a closed track circuit comprising the rails of the track, a track relay, a track battery and a control relay between the battery and track, of front and back contacts for the control relay, a shunt of predetermined resistance around the control relay opening at the back contact of the control relay, a shunt across the track opening at the front contact of the control relay, a second relay in the last mentioned shunt, a front contact for the last mentioned relay, and a low resistance shunt around the control relay and the said first mentioned shunt opening at the front contact of the said second relay.

24. The combination with a closed track circuit comprising the rails of the track, a track relay, a track battery and a control relay between the battery and track, of front and back contacts for the control relay, a shunt of predetermined resistance around the control relay opening at the back contact of the control relay, a shunt across the track opening at the front contact of the control relay, a retarded release relay in the last mentioned shunt, a front contact for the retarded release relay, and a low resistance shunt around the control relay and the first mentioned shunt opening at the front contact of the retarded release relay.

25. The combination with a closed track circuit comprising the rails of the track, a track relay, a track battery and an external battery limiting resistance and a control relay located in the circuit between the battery and track, of a front contact for the control relay, a shunt across the track opening at the front contact of the control relay, a second relay in said shunt, two front contacts for the last mentioned relay, a low resistance shunt around the control relay opening at one of the front contacts of the second mentioned relay, a shunt around the said external battery limiting resistance and the control relay opening at the other front contact of the second mentioned relay and a supplemental battery in the last mentioned shunt.

26. The combination with a closed track circuit comprising the rails of the track, a track relay, a track battery and an external battery limiting resistance and a control relay located in the circuit between the battery and track, of a front contact for the control relay, a shunt across the track opening at the front contact of the control relay, a retarded release relay in said shunt, two front contacts for the retarded release relay, a low resistance shunt around the control relay opening at one of the front contacts of the retarded release relay, a shunt around the said external battery limiting resistance and the control relay opening at the other front contact of the retarded release relay and a supplemental battery in the last mentioned shunt.

27. The combination with a closed track circuit comprising the rails of the track, a track relay, a track battery and an external battery limiting resistance and a control relay located in the circuit between the battery and track, of front and back contacts for the control relay, a shunt of predetermined resistance around the control relay opening at its back contact, a shunt across the track opening at the front contact of the control relay, a second relay in the last mentioned shunt, two front contacts for the last mentioned relay, a low resistance shunt around

the control relay opening at one of the front contacts of the second mentioned relay, a shunt around the said external battery limiting resistance and the control relay opening at the other front contact of the second mentioned relay and a supplemental battery in the last mentioned shunt.

28. The combination with a closed track circuit comprising the rails of the track; a track relay, a track battery and an external battery limiting resistance and a control relay located in the circuit between the battery and track, of front and back contacts for the control relay, a shunt of predetermined resistance around the control relay opening at its back contact, a shunt across the track opening at the front contact of the control relay, a retarded release relay in the last mentioned shunt, two front contacts for the retarded release relay, a low resistance shunt around the control relay opening at one of the front contacts of the retarded release relay, a shunt around the said external battery limiting resistance and the control relay opening at the other front contact of the re-

tarded release relay and a supplemental battery in the last mentioned shunt.

29. The method of accomplishing pick up of the track relay in a closed track circuit having a track battery and a battery limiting resistance without opening the circuit, which consists in connecting another battery in series with the track battery and in shunt with the said limiting resistance. 30

30. The method of operating a closed track circuit having a battery limiting resistance which consists in increasing the battery limiting resistance when the train shunt is applied and momentarily decreasing the battery limiting resistance upon removal of the train shunt. 35

31. The method of operating a closed track circuit having a track battery and battery limiting resistance which consists in increasing the battery limiting resistance when the train shunt is applied and momentarily closing a shunt around the battery limiting resistance upon removal of the train shunt. 40

SAMUEL S. STOLP.

CERTIFICATE OF CORRECTION.

Patent No. 1,626,643.

Granted May 3, 1927, to

SAMUEL S. STOLP.

It is hereby certified that the above numbered patent was erroneously issued to Charles B. Gillson as assignee of the entire interest in said invention whereas said Letters Patent should have been issued to the inventor, said "Stolp" and Charles B. Gillson, said Gillson being assignee of one-half interest only in said invention, as shown by the records of assignments in this office; and that the said Letters Patent should be read with this correction therein that the same may conform to the record of the case in the Patent Office.

Signed and sealed this 14th day of June, A. D. 1927.

Seal.
